UNITED STATES PATENT OFFICE

WILLEM DE GROOT, OF EINDHOVEN, NETHERLANDS, ASSIGNOR TO GENERAL ELECTRIC COMPANY, A CORPORATION OF NEW YORK

GASEOUS ELECTRIC DISCHARGE DEVICE

Application filed January 12, 1933, Serial No. 651,385, and in the Netherlands December 24, 1931.

The present invention relates to gaseous electric discharge devices generally and more particularly the invention relates to such devices the gaseous atmosphere of

5 which comprises a metal vapor.

It has been proposed to use gaseous electric discharge devices of the above type having a cathode which is electron emitting when heated and a gaseous atmosphere comprising 10 a rare gas and sodium vapor as a source of illumination. Various gases such as argon, crypton, or xenon have been used as the rare gas constituent of the gaseous atmosphere heretofore. Applicant has 15 found that the use of such gases in an electric arc discharge lamp device is attended by many disadvantages. In the case of argon, for example, the light emitted by the lamp device after the arc discharge starts 20 and before the sodium vapor, generated from the solid sodium by the heat of the electric arc discharge conducted between the electrodes by the argon gas, is at sufficient pressure to participate in the arc discharge 25 is of no practical value for illuminating purposes.

The object of the present invention is to provide an electric discharge lamp device having a gaseous atmosphere comprising 30 sodium vapor which emits sufficient light to be of practical value for illuminating purposes immediately on the start of the gaseous electric discharge. Still further objects and advantages attaching to the device 35 and to its use and operation will be apparent to those skilled in the art from the following particular description.

The invention attains its objects by using neon as the rare gas constituent of the gaseous atmosphere. Such a lamp device is not only useful as an illuminating means immediately on the starting of the arc discharge, but operates more efficiently and the light emitted thereby has a wider spectrum 45 band than prior devices using sodium vapor alone, or a mixture of sodium vapor and gases other than neon since the neon spectrum supplements the monochromatic spectrum of the sodium light during the 50 operation of the device.

The invention will be readily understood by an inspection of the accompanying drawing and a perusal of the following detailed description thereof.

Fig. 1 of the drawing is a schematic representation of an electric arc discharge lamp device, and

Figs. 2, 3 and 4 are curves showing the relative values of various gases used in the type of electric arc lamp device illustrated in Fig. 1 when operated on direct current.

The electric arc discharge lamp shown in Fig. 1 has an approximately spherical container 1, having a press 2 which projects toward the outside of said container 1. The current-supply leads are sealed into this press 2 and are connected to the electrodes 3 and 4 of the discharge device. The electrode 3 is a coiled cathode which is covered with a layer of earth-alkali oxide and 70 is electron emitting when heated. Two plate-shaped anodes 4 are located a distance of approximately 15 mm. from said cathode 3. The container 1 has a gas filling consisting of neon at a pressure of 2.5 mm. 75 at room temperature. A quantity of sodium is located in said container 1 and the vapor thereof participates in the arc discharge during the operation of the device. In order to diminish the heat radiation from the 80 container 1, said container 1 is enclosed in an envelope 5 having a press 6 into which the current-supply wires of the electrodes are sealed. These wires also support the container 1. The space between the container 1 and envelope 5 is evacuated.

The presence of the neon facilitates the starting of the arc discharge. The heat generated by said discharge heats the sodium present in the tube, whereby the pressure of the sodium vapor is increased. This vapor participates intensively in the discharge whereby a very strong light is emitted by the discharge lamp device. The temperature of container 1 is high and the 90 pressure of the sodium vapor is that which exists at a temperature of 200 to 300 degrees C. At this pressure, the discharge lamp device is at its maximum efficiency.

The electric discharge between said elec-

trodes 3 and 4 is an arc discharge without a positive column. The starting voltage is 17 v., and the operating voltage of the discharge is 13 v.

5 An impedance, such as a resistance, choke coil, or leakage transformer, is connected in series with the discharge device, acting as a ballast to steady the arc discharge. Such impedance has not been shown for purposes of simplicity.

10 The structural details of the lamps are more fully shown and described in my co-pending application Serial Number 651,384, filed January 12, 1933, to which reference is made for the complete disclosure of said lamp devices.

15 Fig. 2 gives the number of international candle units of the light emitted by discharge devices of the above type as a function of the gas pressure, when such devices have a neon filling, an argon filling, a krypton filling, or a helium filling. The power consumption (including the power required for heating the cathode 3) is approximately 20 the same for the different gas fillings; that is, 53 w. for the neon filling, 57 w. for the argon filling and 58 w. for the krypton filling. The pressure of the gas at room temperature is expressed in millimeters.

25 The curve A gives the relation when neon is used, while curves B and C give the relation when argon and krypton respectively are used. The figures show very clearly that the light emission of a discharge device filled 30 with neon is considerably greater than that of a discharge device filled with argon or krypton. Helium gives more unfavorable results. In Fig. 2, for instance, the line D gives the candle power of a sodium vapor 35 lamp filled with helium. Although the power consumption of a discharge device filled with helium is somewhat smaller than that of a similar discharge device having a filling of neon, argon, or krypton, represented by the curves A, B, C; namely, 44 w., a comparison of these curves shows that the 40 efficiency is considerably smaller than in the case of a discharge device filled with neon, even when the lower energy consumption is 45 taken into account.

50 The curves A, B, C, show a maximum which is not shown in the case of curve D. The maximum of curves B and C is rather sharp, as indicated by dotted projection lines from the knee of the respective curves to the X axis in Fig. 2. The maximum of curve A, however, is not so sharp, as shown by the flatness of that curve on each side of its projection line in Fig. 2. The importance of 55 these relations, as shown by the curves in question, is considerable, because the optimum value of the gas pressure of a neon filling, i. e., the pressure which produces the highest temperature of the vapor component 60 of the filling, within practical limits, is not

as critical as that of an argon or krypton filling. Furthermore, the optimum neon pressure is higher than the optimum argon and krypton pressure which is advantageous 70 since a relatively large quantity of neon must be placed in the container 1 which gives a longer life to the device as this large quantity of neon does not disappear as rapidly as the smaller quantities of argon and krypton. 75

80 In Fig. 3, a few more curves E, F, G and H of discharge devices with containers of other dimensions are shown. The diameter of the container used for determining the curves of Fig. 2 was 50 mm., the diameter of the container of the device used in determining the curves E and F was 60 mm. and the diameter of the container of the device used for determining curves G and H was 45 mm. 85

90 Line E is for neon filling and a power consumption in the discharge device (including the power for heating the glow cathode 3) of 90 w., while curve F applies to an argon filling and a power consumption of 85 w. Curves G and H were determined by a power consumption of 53 w. and a gas filling of neon or argon respectively. This figure again shows clearly that the use of neon has great advantages.

95 For any practical size and spacing of the electrodes the optimum pressure of the neon filling proves to be somewhat dependent on the size of the surface of the container of the discharge device. In Fig. 4, this optimum pressure has been plotted as a function 100 of the surface (curve K). The pressure is measured in millimeters at room temperature and the surface is measured in square centimeters. The figure shows that the neon pressure should preferably be less than 4 105 mm. at room temperature. The figure further shows clearly that the optimum pressure depends on the size of the surface according to a linear function. Figs. 2 and 110 3 show that the pressure of the neon may be somewhat higher or somewhat lower than the optimum value without any great disadvantage.

115 As the curves A, E and G are rather flat at the maximum, a change in the neon pressure around the optimum value causes only a slight decrease in the light emission. The favorable values of the pressure are located in a field above and below the curve K, as shown in Fig. 4, represented in the area 120 limited by the straight lines L and M. The straight lines L and M are represented by the functions $p=3.3-11.5 \times 10^{-3} \times Q$ and $p=1.1-4 \times 10^{-3} \times Q$ respectively where p is the pressure in mm. and Q is the size of the surface of the bulb in square centimeters. It is, therefore, preferable that the neon pressure lie between the maximum and minimum values given by these equations.

125 While I have shown and described and 130

have pointed out in the annexed claims certain novel features of the invention, it will be understood that various omissions, substitutions and changes in the forms and details of the device illustrated and in its use and operation may be made by those skilled in the art without departing from the broad spirit and scope of the invention.

What I claim as new and desire to secure by Letters Patent of the United States is:—

1. An electric discharge lamp device comprising a container, electrodes sealed therein, a gaseous atmosphere therein comprising sodium vapor and neon, the gaseous electric discharge between said electrodes being an arc discharge, and means for maintaining said container at a temperature from 200 to 300 degrees C.

2. An electric discharge lamp device comprising a container, electrodes sealed therein, a gaseous atmosphere therein comprising sodium vapor and neon, the neon pressure

being less than 4 mm. at room temperature, the gaseous electric discharge between said electrodes being an arc discharge and a heat retaining envelope surrounding said container and spaced therefrom.

70

3. An electric discharge lamp device comprising a container, electrodes sealed therein, a gaseous atmosphere therein comprising sodium vapor and neon, the pressure of the sodium vapor being that which exists at 75 temperatures between 200° to 300° centigrade during the operation of the device, and the gaseous electric discharge between said electrodes being an arc discharge.

4. A hot cathode gas lamp having a substantially spherical container from 50 to 60 mm. in diameter, and a gaseous filling for said container comprising neon gas under from 1 to 3.5 mm. pressure at room temperature in combination with sodium vapor.
